HAND TRUCK

Walter E. Summerhill, Chardon, Ohio, assignor
to The National Screw & Manufacturing Com-
pany, Cleveland, Ohio, a corporation of Ohio

Application September 14, 1950, Serial No. 12,189

Term of patent 14 years

(Cl. D14—3)

To all whom it may concern:

Be it known that I, Walter E. Summerhill, a citizen of the United States, residing at Chardon, in the county of Geauga and State of Ohio, have invented a new, original, and ornamental Design for Hand Truck, of which the following is a specification, reference being had to the accompanying drawing, forming a part thereof, in which

Fig. 1 is a perspective view of a hand truck, embodying my new design with the receptacle embracing loop shown in an elevated position;

Fig. 2 is a side elevational view of the truck with the receptacle embracing loop shown in lowered position;

Fig. 3 is a top plan view of the truck with the receptacle embracing loop in the position shown in Fig. 2;

Fig. 4 is a front elevational view of the truck with the receptacle embracing loop in the position shown in Figs. 2 and 3; and

Fig. 5 is a fragmentary rear elevational view of the truck.

My design for hand truck shown, is characterized by the configuration of the foot portion.

The receptacle shown in dotted lines in Figure 2 is for illustrative purposes only.

I claim:

The ornamental design for a hand truck, substantially as shown and described.

WALTER E. SUMMERHILL.
